AUXILIARY AIR FURNISHING DEVICE

Philip C. Nilles and Joseph A. Steffen, Chicago, Ill.

Application June 25, 1946, Serial No. 679,254

2 Claims. (Cl. 277—60)

1

This invention relates to improvements in auxiliary air furnishing devices for internal combustion and similar motors, having for an objective to provide a device particularly advantageous for supplying additional quantities of air to the gaseous fuel delivered to the motor cylinder combustion chambers through its intake manifold from the motor charge-forming means or carburetor, whereby to complement and admix with the same and thus, materially increase the combustibility thereof, hence, insuring a maximum of firing power efficiency and eliminating the presence of active gaseous tailings which not only effect fuel waste but, also, occasion ill-economies in that the same find their ways into the motor crank case and detrimentally dilute the lubricating oil therein contained.

Moreover, it is an object of the invention to provide a device of the stated character which, when connected to the motor intake manifold and upon operation of such motor, will function to automatically supply additional quantities of air to and for admixture with the gaseous fuel flowing through said manifold from the motor charge-forming device, the volume of such quantities of air being proportioned or regulated according to the degree of suction in the manifold, so that when the suction increases, as when the motor throttle is substantially closed, i. e., the motor is idling, the supply of additional air will be proportionately increased in effectual ratio to the amount of gaseous fuel then being drawn from the charge-forming device into the firing chambers of the motor cylinders, thus, perfecting its combustibility and insuring the attainment and maintenance of maximum motor performance and operating economies.

It is also an object of the invention to provide the device with adjustable suction responsive means for controlling or governing resistance to movement of the valves of the device in their respective chambers and from their seats, and to so house such means as to afford them with positive protection from foreign means and disturbances of the particular adjustments thereof.

It is a further object of the invention to provide one of the valve means of the device with ports so arranged in its casing that when progressive movement of the valve therein is effected by the application of the engine created suction thereto, proportionately greater or increased quantities of air will be admitted to and for admixture with the combustible charge flowing from the charge-forming device into the motor intake manifold; the intaking of such automatically

2

controlled quantities or volumes of air being capable of being discontinued by mechanical means at the desire or option of a user.

Yet another object of the invention is to provide a device of the character mentioned, whose elements of construction are so designed and assembled as to permit convenient and ready access to be had to its working parts for adjustment, cleaning, repair or the like.

Other objects of the invention will be in part obvious and in part pointed out hereinafter.

In order that the invention and its mode of operation may be understood by those skilled in the art to which it appertains, we have in the accompanying illustrative drawing and in the detailed following description based thereon, set out one possible embodiment of our invention.

In the drawing:

Figure 1 is a more or less schematic side view 20 of a combustion motor having its intake manifold equipped with the invention;

Figure 2 is a side elevation of the improved device;

Fig. 3 is a longitudinal section through the 25 same;

Figure 4 is a transverse section taken on the line 4—4 of Figure 3, looking in the direction in which the arrows point.

Figure 5 is a similar section taken on the line 30 5—5 of Figure 3, looking in the direction in which the arrows point.

Figure 6 is a similar section taken on the line 6—6 of Figure 3, looking in the direction in which the arrows point.

Figure 7 is a transverse section similar to Figure 6, but wherein the sleeve valve is shown in closed position with respect to the air intake ports of the adjacent valve casing, and

Figure 8 is a transverse section taken on the line 8—8 of Figure 3, looking in the direction in which the arrows point.

Having more particular reference to the drawing, in connection with which like characters will designate corresponding parts throughout, 45 M indicates the intake manifold of an internal combustion motor of the multiple cylinder type having our improved device operatively connected thereto. The device is indicated in its entirety by the reference letter D. It comprises a 50 casing 1, made of metal or other suitable material, substantially cylindrical in form. Co-axially disposed chambers 2 and 3 are formed in the longitudinally opposite portions of said casing 1 and open onto the adjacent ends of the 55 same; a medially located longitudinally disposed

way 4 being formed in the intermediate portion of the casing and intercommunicatively connecting said chambers 2 and 3. The inner open end of the chamber 2, i. e., the adjacent end of the casing 1 is ground or otherwise prepared to provide a valve seat, the purpose of which will be presently described, while a plurality of radially disposed air-inletting ducts, generally designated by the numeral 5, are formed in the sides of said casing and are so positioned as to communicate with the inner end portion of the chamber 2, as shown in Figure 3.

The opposite end portions of the casing 1 are preferably externally screw-threaded, as at 6. Engaged with that screw-threaded portion 6 of the casing 1 adjacent the chamber 2, is a T-fitting or coupling 7, having the ends of its head portion internally screw-threaded and one thereof engaged with the adjacent screw-threaded portion 6 of the casing 1. The leg portion of the T-fitting, indicated at 8, has its free end externally screw threaded and thus, provides means for effecting connection of said fitting with an appropriate portion of the intake manifold M, by way of a suitable internally screw-threaded opening formed therein. Thus, an operating and supporting connection will be effected between the devices and the charge-forming device or carburetor C.

The outer or remaining screw threaded portion 6 of the casing 1 has a cap 9 engaged therewith, said cap being provided with an externally located opening 10 in its outer side communicating with the chamber 2.

A stem valve 12 is arranged within the casing 1 and as will be noted upon reference to Figure 3, its head 11 is adapted to be normally seated upon the ground or otherwise prepared seat portion of the body 2 over the open inner end of the chamber 3 in spaced relation to the aforesaid air-inletting ducts 5. A perforate disc or plate 11' is engaged and fixedly arranged in the open inner end of the chamber 2 and a centrally located opening therein slidably receives an adjacent portion of the valve stem 12 therethrough. The valve stem is longitudinally disposed throughout chambers 2 and 3 an intermediate portion thereof being snugly and slidably received in the way 4. The free or remaining portion of the stem 12 extends through the opening 10 in the cap 9 beyond the chamber 2 and is preferably screw-threaded, as at 13. Engaged over and about the valve stem 12 is an expansion type of helical spring 14, whose inner end has bearing engagement with the inner end wall of the chamber 2, while its outer end has bearing engagement upon a tension adjusting nut 15 turned into engagement with the screw-threaded portion 13 of the stem 12. If desired, a locking nut 15' may be turned onto said screw-threaded portion 13 into abutting engagement with the tension adjusting nut 15, for an obvious purpose.

It may be here noted that the positioning of the free or outer end of the valve stem 12 aligns with the opening 10 in the cap 9, as shown in Figure 3.

Due to the mode of connection between the screw threaded inner end 6 of the casing 1 and the T-fitting 7, it will be understood that relatively longitudinal adjustment may be effected between these two elements at certain times, whereby to increase or decrease the internal area of the chamber thus provided within the head of said fitting; also, that by reason of this adjustability between the engaged end of the cas-

ing 1 and the head of the T-fitting 7, the former may be turned upon the latter, at times, to insure absolute fluid-tightness of the device, such for example, as may be required in the instance of wearing of the engaged elements. Moreover, by reason of the screw threading of the outer end of the casing 1, it will be understood and appreciated that the internally screw-threaded cap 9 may be longitudinally adjusted with respect to said end of the casing in order that the free end of the portion of the stem 12 may, at times, be completely housed within and protected by said cap 9 against interference from foreign objects.

A second casing 16 is provided the device and is made of metal or other suitable material, preferably in substantially cylindrical form. A chamber 17 is provided within the casing 16 and has a perforate wall 18 formed in its normally inner end. Its outer end is open and is adapted to be normally closed by the screw-threaded engagement of a closure cap 19 thereover, as is also shown in Figure 3. The inner end of the casing 16, i. e., that end provided with the perforate wall 18, is externally screw-threaded and is adapted to be turned into fixed engagement with the remaining end of the head of the T-fitting 7 in opposed relationship to the casing 1. A plurality of circumferentially arranged air-inletting ducts 20 are formed in the side walls of the casing 16 in proximity to the normally inner portion thereof and as will be noted, upon reference to Figure 2, extend over an intermediate portion of said casing 16. To control communication between the chamber 17 and the atmosphere or outside, a sleeve-valve 21 is snugly and rotatively engaged over and about the intermediate portion of the casing 16 and is provided with ports generally indicated by the numeral 22, corresponding in number and placement with that of the adjacent air-inletting ducts 20. Thus, by rotation of the sleeve-valve 21 to a predetermined position, its ports 22 may be registered with the air-inletting ducts 20. By rotation of said sleeve in an opposite direction, said air-inletting ducts 20 may be closed. To facilitate rotation of the sleeve-valve 21, an arm 23 is fixedly connected with the same and is adapted to be engaged by a suitable manually operable motion transmitting means 24 engaged at one end with an outer portion of said arm 23, as at 25, and having its remaining or free end extended to a point remote from said arm 23.

A cylindrical cup-like valve 26 is snugly and slidably received in the chamber 17 of the casing 16 and during its longitudinal movement, at times, therein, is adapted to cover or uncover certain or all of the air-inletting ducts 20, thus controlling atmospheric communication with the chamber 17. An expandable coiled spring 27 is longitudinally arranged in the chamber 17 of the casing 16 and one end thereof has fixed bearing engagement with an adjacent side of the perforate wall 18, while its opposite end portion is received in the cup-like slidable cylindrical valve 26 and has bearing engagement with its bottom. Thus, it will be understood that the action of the adaptable spring coil is such that the valve 26 will be normally retained in a position adjacent the outer end portion of the casing 16; however, that inward sliding movement of said valve in the chamber 17 will be permitted.

In order that the valve 26 may have the extent of its outer sliding movement in the casing 16 limited or regulated as desired or required, we engage a set screw 28 through a screw threaded

opening from the outer end of the cap 19, as shown in Figure 3, the inner end of such set screw having bearing engagement with the adjacent portion of the cylindrical valve 26. Consequently, an adjustable stop will be provided said valve 26. If desired, a locking or jam nut 29 may be engaged with the screw-threaded portion of the said screw 28 whereby to releasably lock the latter in an adjusted position.

In operation of our improved device and assuming that the same is connected to the motor intake manifold, as hereinbefore described, when the equipped motor is operating to effect within the intake manifold M a suction measuring slightly under 18 inches, it will be seen that the valve 26 within the casing 16 will be drawn inwardly by reason of the influence of such suction thereupon, to a position within said casing where certain of the air inletting ducts 20 will remain open or uncovered. Hence, a sufficient amount of air will be permitted to pass therethrough into the casing 16 for discharge into the connection 8 of the T-fitting 1, thus assuring combustibility of the gaseous fuel flowing from the charge forming device C. When the degree of suction within the intake manifold M is well under 18 inches, it will be seen that the tension of the coiled spring 27 engaging the valve 26 will be sufficient to counteract the applied influence of such suction and to force said valve outwardly in the chamber of its casing 16, thus causing the remaining, or at least, a greater number of said air inletting ducts 20, to be open or uncovered. Consequently, greater volume of air, that is to say, air in sufficient quantities will be supplied through the T-fitting 1 and its connection 8 to the motor intake manifold M whereby to maintain or effect satisfactory combustibility of the gaseous charge passing therethrough to the motor cylinders.

When motor operating conditions different from the foregoing prevail in a motor equipped with our improved device, i. e., when suction measuring over 18 inches is effected by the pistons working in the motor cylinders and is transmitted to the intake manifold M, combustible or carbureted gaseous fuel will be drawn from the motor charge-forming device or carburetor C through the manifold M into the combustion or firing chambers of the motor cylinders. When this suction reaches a pre-determined degree, i. e., a point where it is desirable or advantageous that an additional or auxiliary supply of air (other than that furnished by the charge-forming device or carburetor C) be admixed with the gaseous fuel flowing through the intake manifold M to increase its combustible characteristics, it will be seen that the increased suction will cause the valve 26 to be drawn inwardly in its casing 16 against the tension of the spring 27, thus, closing or covering all of the air inletting ducts 20 in said casing 16. At the same time, and by reason of the increased degree of applied suction, the valve 11 will be drawn inwardly or away from its seat adjacent the chamber 2. As the result of this opening of the valve 11, a properly metered supply of additional air will be drawn into and through the T-fitting 1 and its connection 8 via the air ducts 5 in the casing 1. The thus secured additional supply of air will admix with the fuel now flowing through the intake manifold M so that when the same is ultimately discharged into the combustion or firing chambers of the equipped motor cylinders, a maximum combustion or firing performance and economical

fuel consumption will be effected, together with a materially increased power production.

The amount of air flowing through our improved device into the motor intake manifold M, it will be understood, will be automatically regulated according to the degree of suction existing within the intake manifold M—that is, the speed or character of operation of the equipped motor. In point with this, it will be understood that when 10 the intake manifold suction decreases to a point less than the resistance of the tensioned coiled spring 14, said spring will immediately operate to automatically return the valve 11 to its closed position with respect to the chamber 2. And 15 when such suction is under approximately 18 inches, said valve 11 will have been returned to its closed position and valve 26 will operate in the manner hereinbefore-described. In line with this statement, it will be understood that the 20 spring 14 of the valve 11 has its tension so adjusted that when the degree of suction (partial vacuum) is 18 inches or over, said valve 11 will be caused to be drawn from its seat in the chamber 2 to admit a supply of air, in the manner 25 above described.

When an equipped motor is working at high speeds, and under normal labor or stress, it is an established fact that the degree of suction within the manifold M will be decreased and at a substantial minimum. Therefore, under such motor operating conditions, the degree of suction may well be under 18 inches. At such times, it will be understood that the spring 14 of the valve 11 will retain the latter in its closed position adjacent the chamber 2 and that the valve 26 sliding within the casing 16 will then function against the influence of the previously tensioned spring 27, to admit automatically proportioned quantities of air through its air-inletting ducts 20 via the connection 8 of the T-fitting 1 into the motor intake manifold M.

It will be thus understood that our improved device may be accurately regulated to admit properly proportioned or metered quantities of air so proportioned that when admixed with the gaseous fuel flowing through said intake manifold, will absolutely perfect the combustible properties or qualities thereof.

Under certain operating conditions it may become desirable to employ two or more of our improved devices upon the intake manifold of a motor and, of course, such conditions or requirements are comprehended by the invention.

With pitting or similar deterioration or wearing of the valve seats, the valve head 11, or the 55 slideable valve 26, or its casing 16, access may be readily had to such parts of the device by merely removing them from the T-fitting 1, whereupon the necessary repairs or replacement of parts, as 60 conditions require, may be effected.

Manifestly, the construction shown is capable of further modification, and such modification as is within the scope of our claims, we consider within the spirit of our invention.

65 We claim:

1. An auxiliary air furnishing device of the character described, comprising relatively opposed casings (each open at both ends), one of said casings having relatively opposed chambers in its opposite portions and each thereof opening onto the adjacent end of the casing and a way formed longitudinally of the casing between the said chambers communicating with each thereof, one of the chambers having air-inletting ducts 70 formed in its walls communicating with the same

in proximity to the inner end of said one of the casings, a valve seated adjacent the inner end of said one of the casings over the adjacent end of the corresponding chamber, a stem on said valve slidably engaging through said way and having its free end portion extended longitudinally into the remaining chamber, springs means engaging the valve stem and a portion of said remaining chamber, means on the free portion of the stem outwardly of said spring means for adjusting the tension of the latter, the remaining casing having a plurality of relatively staggered air-inletting ducts formed about its side wall, a cylindrical valve slidably received within said remaining casing, means for normally maintaining said valve adjacent the outer end of the said second casing, a ported sleeve-valve engaged about the side wall of said second casing cooperable with the air-inletting ducts therein, means closing the

outer end of said casing, and means engaged with the respective inner ends of each of said casings for connecting the same to a manifold.

2. An auxiliary air furnishing device, comprising relatively opposed casings each having a way in the inner end thereof and each of said casings having air-inletting means in its respective wall beyond its said way, spring engaged valve means normally seated adjacent and over the way of one casing, a spring engaged cylindrical valve slidably received in the remaining casing normally arranged beyond the air-inletting openings in said remaining casing, and means engaging the adjacent ends of the opposed casings for communicably connecting the same to an intake manifold.

PHILIP C. NILLES.
JOSEPH A. STEFFEN.
